ELASTIC MATERIAL

Richard Hesse, Easthampton, Mass., assignor to
 United Elastic Corporation, Easthampton,
 Mass., a corporation of Massachusetts

Application June 14, 1950, Serial No. 168,108

1 Claim. (Cl. 139—421)

1

This invention relates to an improved woven material and particularly to material of the elastic webbing type in which covered rubber threads are utilized to produce an elastic webbing suitable for use as a belting material in forming waist bands, belts, and the like.

In women's wearing apparel of the type including a blouse and skirt ensemble, it is sometimes difficult to maintain the waist band or top portion of the skirt snugly in place over the bottom portion of the blouse, without actually attaching the garments to one another, and it is especially difficult to hold the blouse from pulling out around the waist band when the wearer is engaged in physical activities.

The present invention is concerned with the matter of more securely holding blouse and skirt ensembles in proper relative position, and aims to devise a belting material for more positively resisting the tendency of such garments to slip away from one another and become separated when the wearer is engaged in physical activities. It is also an object of the invention to provide a waist band which may be used without being attached to either the skirt or blouse, and which includes means for simultaneously securing the skirt and blouse together with an improved holding action. Still another object of the invention is to provide an improved method of weaving elastic webbing in which novel gripping surfaces are formed.

These and other objects and novel features will be more fully understood and appreciated from the following description of a preferred embodiment of the invention selected for purposes of illustration and shown in the accompanying drawings, in which

Fig. 1 is a fragmentary enlarged plan view of a preferred form of the elastic material of the invention;

Fig. 2 is an elevational view of the elastic material taken along one edge thereof;

Fig. 3 is an enlarged fragmentary cross-sectional view taken on the line 3—3, of Fig. 1;

Fig. 4 is an enlarged fragmentary cross-sectional view taken on the line 4—4 of Fig. 1; and

Fig. 5 is an enlarged fragmentary cross-sectional view taken on the line 5—5 of Fig. 1.

In general, the invention comprises a strip of elastic material provided with groups of raised rubber friction surfaces or knobs arranged to stand out from the side or sides of the elastic material in a position to develop novel gripping effects on fabrics and other bodies with which the friction surfaces may be brought into contact.

In one preferred embodiment the elastic material is employed in a length suitable for constituting a separate belt or waist band and raised rubber gripping surfaces are provided on both sides of the belt or waist band. It is intended that this belt be worn with a blouse and skirt, or slacks ensembles, in such relationship to these garments as to completely encircle the bottom portion of the blouse and to lie between the blouse and the inner waist band of the skirt or slacks, and to contact both garments so that the raised surfaces on one side of the belt may engage against the blouse while the raised surfaces on the other side may engage with the overlapping skirt or slack portions.

Referring more in detail to the drawings, Fig. 1 illustrates a strip of elastic webbing generally denoted by the arrow A and including covered rubber strands 8 and 9 woven together with groups of uncovered rubber strands, such as shown at 10, 12, 14 and 16. In accordance with the invention the uncovered rubber strands are caused to stand out from opposite sides of the webbing to produce raised rubber surfaces which are formed to provide a novel gripping action derived in part from a multiplicity of tiny friction edges present in the raised surfaces, and in part from the ability of the raised rubber strand portions to stretch and contract upon themselves both longitudinally and transversely of the belting.

As will be noted from an inspection of Fig. 1, the raised rubber surfaces may be repeated throughout the webbing A, for example in spaced-apart groups, to form one or more rows which extend longitudinally of the webbing and the raised rubber surfaces in any one row may be arranged in staggered relation with respect to the raised rubber surfaces of an adjacent row.

In each of the groups of raised surfaces the constituent rubber strands extend side by side longitudinally of the belting. Each strand is so woven into the webbing 8 as to provide a series of projecting loops and the rubber portions of the strand constituting these loops are in an unstretched or relatively lightly stretched condition. Also, the loops of one strand in a given raised surface occur in closely compacted but staggered relation to the loops of an adjacent strand, with the result that each raised surface, in effect, is a composite friction surface made up of a number of curved or rounded rubber crowns. Each loop or crown has edges which are offset from those of adjacent loops or crowns, as will be fully apparent from an inspection of the loops in strands 10 and 12, shown in Fig. 2. These

edges cooperate with one another to exert a strong frictional gripping action with respect to a fabric which is moved transversely across the rubber loops.

Moreover, each one of the loops constitutes strand portions which are in a relatively relaxed or unstretched condition, permitting the raised rubber surfaces to expand and contract upon themselves when the elastic webbing is flexed or stretched during wear. There is thus developed a novel gripping effect which may be increased by increasing the number of rows of the groups and which is especially suited for engagement with the fibers of fabrics coming into contact with the raised rubber surfaces.

In their relaxed state the looped portions, if lying in contact with a fabric surface, tend to yield and spread apart when the fabric is moved transversely with respect to the strip. Since the looped portions are resilient, they will tend to draw together again and to grasp and hold between one another tiny fibers of the fabric portion contacted. It is pointed out that this holding and gripping effect on fibers of a fabric may take place either between the loops of adjacent strands or between the succeeding loops of a single strand. In the former case the gripping effect is largely developed by directly opposing a sliding movement of a fabric transversely across the strip. In the latter case, holding and gripping action develops as a result of stretching the strip of webbing longitudinally of itself, such as may occur with body movements, thus extending the looped portions. As the looped portions of any one of the strands contract, they tend to stick to, and draw between them, fiber ends of a fabric lying in contact with the raised surface.

A further important feature of the invention is the provision of the raised surfaces on both sides of the elastic webbing A, in the manner illustrated in Fig. 2, in order to provide dual gripping surfaces. This relative arrangement of raised surfaces is achieved with the same strands which form the first noted raised surfaces, and is conveniently carried out, for example, by weaving each of the strands of any one group so that they are raised out of one side of the webbing for a certain number of picks and then alternately raised from the opposite side of the webbing for another series of picks corresponding to the said first series. This procedure is repeated throughout the length of the webbing.

Such an operation has been diagrammatically indicated in Figs. 2, 4 and 5, in which the woven position of strand 10 in the threads or strands of the webbing 8 is illustrated. It should be understood, however, that the specific weaving arrangement set forth in the drawings may be varied in different ways to produce modified forms of raised gripping surfaces.

In using the dual gripping surfaces at opposite sides of the elastic webbing, it is, as noted above, intended that the strip or belt made therefrom be placed over the lower portion of a garment, such as a blouse, or similar piece of wearing apparel, and for purposes of illustration this member has been shown fragmentarily in cross-section in Fig. 2 and denoted by the numeral 29. At the other side of the belt which may be constituted by the strip A illustrated in Fig. 2, there may be disposed a waist band or similar portion of a skirt, slacks, or other type of wearing apparel which has been diagrammatically indicated in cross-section by the nu-

meral 22. It will be seen that the raised rubber surfaces occurring on opposite sides of the elastic webbing are thus positioned between the two garment portions in a position such that they may exercise a gripping effect on each of the garments, thus functioning to hold them in a relatively fixed position with respect to one another and serving especially to prevent the edges of the member 20 from being pulled away from overlapping portions of the member 22.

In this type of application of the invention it will readily be observed that as the strip is stretched longitudinally of itself, the adjacent loop portions of any one of the strands will be drawn apart from one another and as they contract while in contact with the surface of the garment 20, will seek to grip the fibers thereof. A similar gripping action is developed by any one of the strands with respect to fibers of the outer garment 22.

It will be apparent from the foregoing description that I have provided an improved elastic material especially suited for use as a belting material. It should be observed that a dual gripping effect is thus simultaneously achieved in which the spaced-apart groups of rubber surfaces on one side are complemented by groups of raised surfaces on the other side so that for a given side of the elastic material there will occur two groups of raised surfaces with an intervening depressed or recessed area while, on the opposite side of the material there will occur groups of raised surfaces at points directly opposite to the points of recessing in the first noted side.

While I have shown preferred embodiments of the invention, it should be understood that changes and modifications may be resorted to in keeping with the spirit of the invention as defined by the appended claim.

Having thus described my invention, what I desire to claim as new is:

In an article of manufacture, a woven elastic fabric stretchable both longitudinally and transversely, a plurality of spaced apart groups of elastic strands, the elastic strands in each group being in side by side relation and woven into the fabric, each group of elastic strands projecting outwardly of the fabric to provide a plurality of raised frictional loops, the spaced apart groups being at each side of the fabric with the groups in staggered relation, the elastic loops of each group having edges which are offset from those of adjacent loops and the individual loops being in unstretched condition, whereby the loops upon stretching of the fabric may expand and contract and tend to draw together for binding fibers of adjacent fabric portions.
